George K. Pappazoglidis*

By John Jochum Jr. Atty.

UNITED STATES PATENT OFFICE.

GEORGE K. PAPPAGOGLIDIS, OF CHICAGO, ILLINOIS.

SAUSAGE-LINKING MACHINE.

Application filed April 13, 1923. Serial No. 631,748.

To all whom it may concern:

Be it known that I, GEORGE K. PAPPAGOGLIDIS, a citizen of the United States, residing at Chicago, in the county of Cook 5 and State of Illinois, have invented certain new and useful Improvements in Sausage-Linking Machines, of which the following is a specification.

This invention relates to improvements in 10 sausage linking machines, and one of the objects of the invention is to provide an improved machine of this character, having means operating to shape the filled casing into links and also provided with means for 15 twisting the links with respect to each other to form a twisted connecting portion between adjacent links.

A further object is to provide improved 20 twisting means for the links which will operate to twist one of the links in one direction and the next adjacent link in the opposite direction, so that the connecting portions between the links will be alternately twisted in opposite directions.

25 A further object is to provide an improved machine of this character, which will be simple, durable, cheap and compact in construction and effective and efficient in operation.

30 To the attainment of these ends and the accomplishment of other new and useful objects as will appear, the invention consists in the features of novelty in substantially the construction, combination and arrangement of the several parts hereinafter 35 more fully described and claimed and shown in the accompanying drawings illustrating this invention, and in which

Figure 1 is a side elevation of a portion 40 of a machine of this character.

Figure 2 is a top plan view of Figure 1.

Figure 3 is a top plan view of the twisting mechanism with portions of the machine removed and showing the parts in one position.

Figure 4 is a view similar to Figure 3, showing the parts in another position.

Figure 5 is a detail sectional view taken on line 5—5, of Figures 3 and 4.

50 Referring more particularly to the drawings, the numeral 10 designates generally a supporting structure, which may be of any desired size and configuration and constructed of any suitable material.

55 Mounted upon the structure are spaced pulleys 11—12, over which an endless flex-

ible carrying element 13, such as a belt, operates. One of the runs of the belt passes over a suitable support 14 and motion may be imparted to the belt in any desired or 60 suitable manner.

Arranged along the edges of the runs of the belt 13 which pass over the support 14, are guides 15 for maintaining the casings in position. Disposed adjacent one end of 65 the belt is a rotatable element 16, the periphery of which is preferably shaped to form concaved portions 17, having intermediate edges 18, which latter are adapted to engage the filled casing as it is fed forward on the 70 belt 13 and beneath the element 16, to divide the casing into links. This element 16 is given a rotary motion in any desired or suitable manner preferably by means of a belt 19, which passes over a suitable pulley 75 connected with the element 16 and preferably over another pulley 20, which is connected for rotation with the pulley 12.

Disposed beneath the belt 13 are twisting elements designated generally by the reference numerals 21 and 22. These elements 21 and 22 are preferably in the form of bars or rods arranged parallel with respect to each other and are movable through suitable guide blocks 23—24. The blocks 23—24 are provided with openings 25—26, through which the elements 21—22 respectively pass and these blocks are mounted for movement in suitable ways 27 in such a manner that the blocks may be moved towards or away 80 from each other. Any suitable means may be provided for moving the blocks 23—24, such as a double screw 28, having an operating handle 29 connected therewith so that when the handle is moved in one direction 85 the guide blocks 23—24 will move in one direction with respect to each other and when the handle is moved in the opposite direction the guide blocks will be moved in the opposite direction with respect to each other; for 90 a purpose to be hereinafter set forth.

Each of these members 21—22 is provided with a yieldable work engaging surface 30, constructed of any suitable material and these surfaces are respectively secured to the elements 21—22 in any suitable manner but are preferably spaced from the respective elements by means of spacing projections 31, over which the elements pass. One end 32 of each of the elements is anchored in any 105 suitable manner. The other end of each of the elements passes over a suitable projec-

tion 33 and is anchored as at 34—35, the projection 33 being so disposed that the point 34 at which the element 30 is anchored will be disposed below the points of engagement 5 of the projections 31 with the element 30 so as to form a recessed portion 36. When the elements 30 are secured to the members 21—22 in the manner just described the recessed portions 36 are so arranged that they 10 will be alternately moved into a position below the end of the conveyor belt 13 as it passes over the pulley 11, as shown more clearly in Figure 2, to form an enlarged space or area into which the sausage link 15 passes as it is delivered from the end of the belt 13. After the casing has been divided into links by the element 16 and as the links are advanced by the conveyor belt 13, one of the links will pass into the recess 36, between the surfaces 30 supported by the elements 21—22, after which the elements 21—22 are reciprocated with respect to each other and in opposite directions to twist the link disposed therebetween and thereby twist 25 the connecting portion between adjacent links. This is accomplished by reason of the fact that the yielding surfaces 30 will engage opposite sides of the link. When the elements 21—22 have reached the limit of 30 their reciprocating movement in one direction, the direction of movement will be reversed, at which time the recess 36 of the other yielding surface will be positioned as shown in Figure 4 to receive the next adjacent link and as the direction of movement of the elements 21—22 will be reversed with 35 respect to each other, the next link which has been fed from the belt will be twisted in a direction opposite to the direction of twisting of the previous link, so that the connecting portion between the next two adjacent links will be given a twisting movement in a direction opposite to the direction of twist of the next previous link. In other 40 words, the links will be alternately twisted first in one direction and then in the opposite direction.

Any suitable means may be provided for reciprocating the elements 21—22, such as a 50 crank shaft 37 journaled in suitable bearings upon the supporting structure. This shaft 37 is provided with cranks 38—39 connected respectively by means of links 40—41 with the elements 21—22. The points of 55 connection of the links 40—41 with the respective elements 21—22 are preferably formed by means of extended laterally projected ends 42—43 of the links, so as to permit the elements 21—22 to be shifted laterally with respect to each other and with 60 respect to the links 40—41 during their reciprocating movement so as to permit these elements to be separated sufficiently that when the direction of movement is reversed 65 they will not engage the link which has just

been twisted, and thereby untwist the same. This lateral movement in other words, permits the surfaces 30 to be moved away from the work.

The lateral shifting movement may be accomplished in any suitable manner but preferably by means of cams 44—45, disposed on opposite sides of the member 21 and adjacent opposite ends of the surfaces 30 and similar cams 46—47 connected with the element 22. These members 21—22 respectively pass through the openings 25—26 in the guide blocks 23—24, one pair of each guide blocks being arranged adjacent each end of the elements 21—22 and in positions that the cams 44—46 at one end of the elements will co-operate with one pair of guide blocks and the cams 45—47 at the other end of the elements 21—22 will cooperate with the other pair of guide blocks, so that when the cams engage the respective guide blocks the members will be respectively given lateral movements with relation to each other. Obviously the respective cams on the members 21—22 are so arranged that when one of the cams is active the other will remain inactive. The cams 44 and 46 are provided for moving the elements 21—22 laterally in one direction while the cams 45—47 are provided for moving the elements in the opposite direction.

As a means for assisting in holding the elements 21—22 in position so that the lateral strain will not displace the members during the twisting movement, any suitable means 100 may be provided. To that end there may be provided a guide or track 48, which is adjustably secured by means of bolts 49, passing through suitable slots 50 into the supporting structure. A roller 51 is carried by the element 21 and is adapted to pass first on one side and then on the other side of the track 48 during the reciprocation of the member 21. A similar guide or track 52 is secured by means of fastening bolts 53 passing through suitable slots 54 to the supporting structure 10. A roller 55 is carried by the element 22 and is adapted to pass first on one side and then on the other side of the track 52. These rollers 51 and 55 and the tracks 48—52 are so arranged with respect to each other that when one of the rollers passes behind the respective track the other roller will pass in front of its track, as shown more clearly in Figures 3 and 4.

By the provision of the adjustable guide blocks 25, the elements 21—22 may be adjusted laterally with respect to each other to vary the distance between the yielding surfaces 30 so as to compensate varying diameters of the links and when the parts are so adjusted the tracks 48—52 may also be adjusted by reason of the slots 50—54 and the respective bolts passing therethrough. The extended extremities 42—43 of the links 130

40—41 also permit of such lateral adjustment.

The shaft 37 may be rotated in any desired or suitable manner preferably from a drive shaft 56, which receives its motion from any suitable source preferably through the medium of a pulley 57, and the shaft 56 is connected with the crank shaft 37 through the medium of intermediate gearing 58—59—60.

10 It is thought that the operation of this machine will be clearly understood from the foregoing but briefly stated it is as follows:

Assuming the parts to be in the position shown in Figure 2, and assuming that the 15 casing has been fed forward upon the belt 13 to be divided by the element 16 into links, and that the links project over the portion of the belt which passes over the pulley 11, so that one of the links will be disposed in 20 the recessed portion 36 on the element 21, and that motion is imparted to the crank shaft 37. In the position shown in Figure 2, the element 21 has reached the limit of its forward movement, while the element 22 has 25 reached the limit of its backward movement. Further motion to the shaft 37 will cause the elements 21—22 to move in the directions indicated by the arrows in Figure 2. It will therefore be manifest that inasmuch as a 30 link will be disposed between the yielding surfaces 30 of the elements 21—22, and when motion is imparted to reciprocate them in the directions of the arrows in Figure 2, the surfaces will engage the link to twist the 35 latter, the roller 55 passing in front of the track 52 will restrain the element 22 against lateral movement and the roller 51 passing behind the track 48 will permit of a slight lateral movement of the element 21. As 40 soon as the elements 21—22 have reached the limit of their movements in one direction, the cranks 38—39 will pass over the center of the shaft 37 and the direction of movement of the elements 21—22 will be reversed. In the 45 meantime, however, the links will have been advanced so that the twisted link will drop out from between the surfaces 30 to permit another link to pass therebetween and to be twisted in the opposite direction.

50 This operation is continued so that the links will be twisted first in one direction and then in the other direction so long as the links are fed between the elements 21—22.

The twisted links may be caught in any 55 suitable receptacle and conveyed away to any desired point.

While the preferred form of the invention has been herein shown and described, it is to be understood that various changes may be 60 made in the details of construction and in the combination and arrangement of the several parts, within the scope of the claims, without departing from the spirit of this invention.

What is claimed as new is:—

1. A machine of the character described embodying means for feeding the filled casing, means for dividing the material in the casing at spaced intervals to form connected links, and means for twisting the portions of the casing intermediate the links, the last recited means embodying mechanism including continuous work engaging surfaces extending in directions transverse to the direction of feeding movement of the link, for alternately twisting the links in opposite directions. 70

2. A machine of the character described embodying means for feeding the filled casing, means for dividing the material in the casing at spaced intervals to form connected links, and means for twisting the portions of the casing intermediate the links, the last recited means embodying two co-operating reciprocable elements operating to alternately twist the links in opposite directions, each of the said elements including an extended and continuous work engaging surface, said surfaces operating in directions transverse to the direction of feeding movement of the link, and means for reciprocating them one with relation to the other. 75

3. A machine of the character described embodying means for feeding the filled casing, means for dividing the material in the casing at spaced intervals to form connected links, means for twisting the portions of the casing intermediate the links, the last recited means embodying two co-operating and yielding elements adapted to simultaneously engage the link, said elements including continuous work engaging surfaces operating in directions transverse to the direction of feeding movement of the link, and means for reciprocating the elements one with relation to the other to alternately twist the links in opposite directions. 90

4. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, the last recited means including continuous work engaging surfaces operating in directions transverse to the direction of feeding movement of the link, and means for reciprocating the said elements. 100

5. A machine of the character described embodying means for feeding the filled casing, means for dividing at spaced intervals the material in the casing to form connected links, means embodying opposed and oppositely reciprocable elements having con- 110
115
120
125

tinuous work engaging surfaces adapted to engage the link on opposite sides and operating in directions transverse to the direction of feeding movement of the links to alternately twist the successive links to twist the portion of the casing intermediate the ends of adjacent links, means for reciprocating the said elements, and means for laterally shifting the said elements, with relation to each other and during their reciprocating movements.

6. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, means for reciprocating the said elements, and means responsive to the reciprocating movements of the said elements for shifting the elements laterally with respect to each other and during their reciprocating movements.

7. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, means for reciprocating the said elements, means for laterally shifting the said elements with relation to each other, and means for restraining the elements against lateral movement during predetermined portions of the reciprocating motion.

8. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, means for reciprocating the said elements, means for laterally shifting the said elements with relation to each other, and means for restraining the elements against lateral movement during predetermined portions of the reciprocating motion, the last said means embodying a track and roller.

9. A machine of the character described embodying means for feeding the filled casing, means for dividing at spaced intervals the material in the casing to form connected links, means embodying opposed and oppositely reciprocable elements adapted to en-

gage the link on opposite sides and alternately twist the successive links to twist the portion of the casing intermediate the ends of adjacent links, means for reciprocating the said elements, means for laterally shifting the said elements with relation to each other, and means for restraining the elements against lateral movement during predetermined portions of the reciprocating motion, the last said means embodying tracks and co-operating rollers individual to the said elements.

10. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, the work engaging surface of the said elements being continuous in the direction of reciprocation of said elements, and means for reciprocating the said elements, the said elements embodying yieldable work engaging portions.

11. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, said elements including work engaging surfaces which are continuous in the direction of reciprocation of the elements, means for reciprocating the said elements, and means for laterally adjusting the said elements one with respect to the other to compensate varying diameters of links.

12. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends of adjacent links, means for reciprocating the said elements, the said elements embodying yieldable work engaging portions, the said portions being continuous in the direction of reciprocation of said elements, and means for laterally adjusting the said elements one with relation to the other to compensate varying diameters of links.

13. A machine of the character described embodying means for feeding the filled casing, means for dividing at spaced intervals the material in the casing to form connected

links, means embodying opposed and oppositely reciprocable elements adapted to engage the link on opposite sides and alternately twist the successive links to twist the 5 portion of the casing intermediate the ends of adjacent links, and means for reciprocating the said elements, portions of the work engaging surface of the said elements being shaped to form enlarged entrance 10 openings for the reception of the links between said surfaces.

14. A machine of the character described embodying means for feeding the filled casing, means for dividing at spaced intervals 15 the material in the casing to form connected links, means embodying opposed and oppositely reciprocable elements adapted to engage the link on opposite sides and alternately twist the successive links to twist the 20 portion of the casing intermediate the ends of adjacent links, and means for reciprocating the said elements, the said elements embodying work engaging surfaces, said surfaces being shaped to form enlarged 25 entrance openings for the reception of the links between the said surfaces.

15. A machine of the character described embodying means for feeding the filled casing, means for dividing at spaced intervals 20 the material in the casing to form connected links, means embodying opposed and oppositely reciprocable elements adapted to engage the link on opposite sides and alternately twist the successive links to twist the

portion of the casing intermediate the ends 35 of adjacent links, means for reciprocating the said elements, means for laterally shifting the said elements one with relation to the other at predetermined points in the reciprocating movements of the elements, 40 and means operating automatically to restrain the elements against lateral movement in one direction at predetermined points in their reciprocating movements.

16. A machine of the character described embodying means for feeding the filled casing, means for dividing at spaced intervals the material in the casing to form connected links, means embodying opposed and oppositely reciprocable elements adapted to engage the link on opposite sides and alternately twist the successive links to twist the portion of the casing intermediate the ends 50 of adjacent links, means for reciprocating the said elements, and means for laterally shifting the said elements with relation to each other and during their reciprocating movements, the last recited means embodying opposed cams and guides operatively related to each of the said elements, the cams 55 and guides of each element being alternately rendered active and inactive by the reciprocating movement of the respective elements.

In testimony whereof I have signed my name to this specification, on this 5th day of April, A. D. 1923. 65

G. K. PAPPAGOGLIDIS.
